UNITED STATES PATENT OFFICE

2,598,125

RECEIPT HOLDER

Edsel C. Isaacson, St. Paul, Minn.

Application June 19, 1950, Serial No. 169,004

2 Claims. (Cl. 129—23)

I

My invention relates broadly to devices for reception and temporary storage of receipts and the like, and has for its primary object the provision of such a device which may be produced at a minimum of cost, and which may be quickly secured to and removed from a wall or other supporting structure, whereby to provide the greatest convenience to the user.

A still further object of my invention is the provision of a device which may be formed from a single length of wire and a single sheet of thick paper stock.

Another object of my invention is the provision of a device which is extremely light in weight, relatively durable in use, and which may be stored or shipped in flat form.

A still further object of my invention is the provision of a device having a pair of cover members hingedly secured together adjacent their upper edges for upward and outward movements of the front cover with respect to the back cover, and in which said device is supported by a hook which projects transversely through the back member and outwardly through an opening in the front member when the front member is in a closed position, whereby said front cover member will force a receipt upon said hook upon closing movements of said front cover member.

A still further object of my invention is the provision of a device of the class described, in which the cover members are biased toward a closed position.

A still further object of my invention is the provision of a device of the class described having provision for convenient positioning and holding of a pencil or other writing tool.

The above and still further objects and advantages of my invention will become apparent from the following detailed specification, appended claims, and attached drawings.

Referring to the drawings, wherein like characters indicate like parts throughout the several views:

Fig. 1 is a view in front elevation of my novel device;

Fig. 2 is a fragmentary view corresponding to Fig. 1 but showing a different position of one of the parts;

Fig. 3 is a fragmentary view on a reduced scale corresponding to Fig. 1, some parts being broken away;

Fig. 4 is a view in section, taken on the line 4—4 of Fig. 1;

Fig. 5 is a fragmentary view in side elevation, as seen from the left to the right of Fig. 2; and

Fig. 6 is a fragmentary view in front elevation showing a modified form of my novel device.

In the preferred embodiment of my invention illustrated in Figs. 1 to 5 inclusive, the numerals 5 1 and 2 identify front and back cover members preferably formed from a single sheet of flexible resilient paper stock folded backwardly upon itself, as indicated at 3. The fold 3, as shown particularly in Fig. 4, forms the upper marginal edges of the front and back cover members 1 and 2. Fasteners in the form of staples 4 secure the front and back cover members 1 and 2 together. It will be noted that the staples 4 are spaced inwardly from the extreme marginal edges 3 so as to bias the bottom edges 5 and 6 respectively of the front and back cover members 1 and 2 toward a closed position. Preferably and as shown, the front cover member 1, adjacent its lower edge 7, is provided with laterally-spaced vertically-extended slits 8, which are adapted to frictionally receive therein, as indicated in Fig. 1, a pencil or other elongated writing tool 9.

Adjacent its upper edge 3, the front cover member 1 is provided with an elongated opening or slot 10, which is normally closed by an upwardly-extended resilient tongue 11. As shown, the slot 10 and the tongue 11 are formed by cutting through the cover 1 along the generally U-shaped line 12.

A suspension element in the nature of a wire-like stem 13 is provided at its upper and lower ends respectively with hooks 14 and 15, the former of which opens downwardly and the latter of which preferably opens upwardly. Furthermore, the hooks 14 and 15 are disposed substantially ninety degrees, one with respect to the other, for a purpose which will hereinafter become apparent. Preferably and as shown, 35 particularly by reference to Fig. 4, the stem portion 13 extends inwardly through an opening 16 in the back cover member 2 immediately below the marginal edge 3 thereof, and extends outwardly of said cover member 2 through an opening 17 in axial alignment with the opening 16, and finally extends inwardly through the opening 18, which is also in axial alignment with the openings 16 and 17. This threading of the stem 13 through the openings 16, 17, and 18 secures 40 the back cover element 2 to the stem 13 in a manner to prevent lateral movements of the former with respect to the latter. It will be noted that the closed end 19 of the hook element 15 supports the back cover element 2, whereas the 45 free end 20 of the hook element 15 lies between 50 the marginal edges 3 and 6 of the front and back cover members 1 and 2, respectively. The stem 13 is 55 formed from a wire-like resilient material, and the hooks 14 and 15 are formed from a wire-like resilient material.

the opposed faces of the cover members 1 and 2. By reference to Figs. 1 and 4, it will be seen that, when the hook element 14 lies flat against a wall or the like, not specifically identified, so as to receive a nail or other fastening device anchored into and projecting outwardly from said wall, the free end 20 of the hook element 15 projects outwardly through the opening 10 in the front cover member 1 at substantially right angles to the faces of the front and back cover members 1 and 2.

This arrangement of parts is important in that, when the front cover member 1 is moved upwardly and outwardly with respect to the back cover member 2, so as to expose the free end 20 of the hook 15, a receipt or the like A interposed between the free end 20 of the hook 15 and the inner face of the front cover member 1 will be forced upon the hook 15 by the closing action of the cover. The final resting place of the receipts A, so-forced over the free end 20 of the hook element 15, is shown in Figs. 3 and 4. The resilient tongue 11 not only aids in the forcing of the receipt A over the free end 20 of the hook 15 but also constantly shields the free end 20 so as to prevent same from scratching the user or becoming entangled in clothing or the like.

It will be noted that the upper hook element 14, which, preferably and as shown, is in the nature of an inverted V, so as to snugly embrace suspension nails or the like of varying diameters, is of less width than the lower hook 15. Therefore, in order to facilitate shipping in a flatter form, I have found it advisable to hold the hook element 15 flat against the faces of the cover elements 1 and 2, as shown particularly in Figs. 2 and 5.

In the modified form of my device illustrated in Fig. 6, front and back covers are indicated by the numerals 1' and 2' respectively. A portion 21 of the lower end 6' of the rear cover 2' is extended longitudinally and folded backwardly upon itself to form, therebetween and the rear cover 2', an upwardly and laterally opening pocket. The extended portion or flap 21 is held against the back cover 2' by a wire staple or the like 22. The front cover 1' at its lower end portion 5' is cut away to provide a tab 23 one side edge of which is adapted to be inserted into the pocket formed by the folded portion 21 of the back wall 2'. This arrangement is effective in maintaining my novel receipt holder in a relatively flat condition particularly when a plurality of receipts or the like are contained therein.

My invention has been thoroughly tested and found to be completely satisfactory for the accomplishment of the above objects; and, while a preferred embodiment of the same is illustrated in the drawings, it should be obvious that my invention is capable of modification without departure from the spirit and scope thereof, as defined in the appended claims.

What I claim is:

1. In a device of the class described, front and back cover members of sheet material connected at their upper marginal edge portions for outward and upward swinging movements of the front cover member with respect to the back cover member, said back cover member being provided with a central opening adjacent its upper edge, said front cover member being provided with a V-shaped slot aligned with the opening in said back cover member, a suspension element in the nature of a stem having a downwardly-opening hook at its upper end and an upwardly-opening hook at its lower end, said hooks being angularly disposed at substantially ninety degrees with respect to each other, the lower of said hooks being adapted to extend through the opening in the back wall member with its free end projecting through the V-slot in the front wall member, and an upwardly-projecting resilient tongue on said front wall member normally biased toward a position to close said V-slot said tongue being forwardly-displaced by said lower hook when said upper hook is caused to lie flat in a supporting position against a wall surface.

2. The structure defined in claim 1 in which said tongue is formed integrally with said front wall.

EDSEL C. ISAACSON.
